UNITED STATES PATENT OFFICE.

NICOLA VITO MANGO AND LEANDRO MANGO, OF UNION HILL, NEW JERSEY.

CUSPIDOR-SUPPORT.

No. 895,281.

Specification of Letters Patent.

Patented Aug. 4, 1908.

Application filed July 15, 1907. Serial No. 383,849.

To all whom it may concern:

Be it known that we, NICOLA VITO MANGO, a subject of the King of Italy, and LEANDRO MANGO, a citizen of the United States, and 5 residing at Union Hill, in the county of Hudson and State of New Jersey, have invented certain new and useful Improvements in Cuspidor-Supports, of which the following is a specification, such as will enable those 10 skilled in the art to which it appertains to make and use the same.

This invention relates to cuspidors and particularly to supports therefor, and the object of the invention is to provide an improved device of this class by means of which a cuspidor may be supported beneath a desk, a table, a counter, a car seat, steamer seat or other device and conveniently drawn out when required for use and then passed back 20 beneath the desk, table, counter, car seat or other device with which it is connected.

The invention is fully disclosed in the following specification, of which the accompanying drawing forms a part, in which the 25 separate parts of our improvement are designated by suitable reference characters in each of the views, and in which:—

Figure 1 is a front view of a desk provided with our improved cuspidor support; Fig. 2 30 a section on the line 2—2 of Fig. 1 and showing a part of the cuspidor support in section; and, Fig. 3 a section on the line 3—3 of Fig. 2.

In the drawing forming part of this specification, we have shown at *a* in Figs. 1 and 2 35 an ordinary table desk having a top *a*², and in the practice of our invention, we provide a bracket or support *b* having a horizontal tubular arm *b*² and adapted to be secured beneath the back part of the top *a*² of the desk 40 in the manner of a hanger. Within the tubular arm *b*² is placed a telescopic rod or bar *c* which may be tubular in form, if desired, and which is adapted to be drawn out from beneath the top of the desk, as indicated in 45 dotted lines in Fig. 1, and which is provided at its front end with a handle *c*² which is preferably directed upwardly, and connected with the rod or bar *c*, rearwardly of the handle *c*² by means of a clamp or similar device *d*, 50 is a cage or holder *d*² adapted to receive a cuspidor *e*.

The cuspidor *e* is provided with a cover *e*² hinged at one side as shown at *e*³, and within the top portion of the cuspidor is placed an 55 annular inwardly directed flange or rim *f* which forms in the top portion of the cuspi-

dor an annular chamber *g* designed to receive disinfecting material, and the flange or rim *f* which forms, in connection with the side walls of the cuspidor, the annular chamber *g* is preferably perforated so that the disinfecting material placed in the annular chamber *g* will percolate therethrough and fall into the cuspidor. 60

The tubular arm *b*² of the bracket or support *b* is provided near its outer end with internal collars or flanges *b*³, and the telescopic rod or bar *c* is provided at its inner end with a collar or flange *c*³, and the inner collar or flange *b*³ operates in connection with the collar or flange *c*³ to limit the outward movement of the rod or bar *c*. It will thus be seen that our improved cuspidor support 70 comprises telescopic members, one of which is stationary and the other movable, the 75 movable member being longer than the stationary member and that part thereof which projects from the stationary member being provided with a cage or holder adapted to receive a cuspidor, and it will be understood 80 that the cuspidor may be removed from the cage or holder for cleaning or other purposes whenever desired.

Our improvements may be applied to any kind of a desk, counter or table, and may 85 also be applied to car seats, steamer seats, ferry-boat seats and wherever such devices are required.

Having fully described our invention, what we claim as new and desire to secure by Letters Patent, is:—

A cuspidor support, comprising a hanger adapted to be secured beneath a table, desk or other article rearwardly of the front edge thereof and provided with a forwardly ranging arm, a supplemental arm telescopically connected with the first named arm and normally projecting a predetermined distance forwardly thereof, said supplemental arm being provided at its forward end with a handle and rearwardly thereof with a detachable cuspidor holder supported thereover. 95

In testimony that we claim the foregoing as our invention we have signed our names in presence of the subscribing witnesses this 105 12th day of July 1907.

NICOLA VITO MANGO.
LEANDRO MANGO.
